UNITED STATES PATENT OFFICE.

CARL R. SNODGRASS, OF SALEM, OHIO.

HEAT-UTILIZING DEVICE.

Application filed April 21, 1924. Serial No. 708,066.

The present invention relates to a heat utilizing device and has for its principal object to provide a device which is adapted to be used with gas stoves and the like so that two cooking utensils may be heated from the same burner.

Another object of the invention is to provide a device of this nature which is extremely simple and efficient in construction, reliable in operation and well adapted to the purpose for which it is designed.

With the above and numerous other objects in view as will appear as the description progresses, the invention relates to certain novel features of construction, and the combination and arrangement of parts as will be hereinafter more fully described.

In the drawing:—

Figure 1 is a top plan of the device, a portion thereof being shown in section,

Figure 2 is a side elevation thereof,

Figure 3 is a longitudinal vertical section,

Figure 4 is a transverse section,

Figure 5 is a plan view of an attachment used with the device, and

Figure 6 is a detailed section taken on the line 6—6 of Figure 1 looking in the direction of the arrow.

Referring to the drawing in detail it will be seen that the device consists of a pair of spaced bars 1 to one end of which are connected a semi-circular band 2 which is provided with a depending apron 3 that is adapted to encircle the flame in the stove to form a heat chamber. The upper edges of the bars 1 are slanted so as to extend upwardly from the band 2. A U-shaped band 4 is attached to the other ends of the bars 1 and its legs are provided on their upper edges with notches 5. A deflector plate 6 is arranged over the upper edges of the bars 1 so as to deflect the heat in the chamber formed by the band 2 to the chamber formed by the band 4. A zig-zag band 7 is arranged

about the band 2 so as to prevent cooking utensils placed on band 2 from tilting. A similar band 8 is arranged about the band 4 so as to form triangular compartments 9 one at each of its legs and body portion. When a cooking utensil is situated on the band 4 the heat will be passed through the notches 5 into the compartments 8 and 9 adjacent the legs of the band 4 but not into the compartment adjacent its body or intermediate portion. The triangular chambers 8 and 9 in which the heat is allowed to pass are provided with outlet notches 10 as shown in Figure 6 at the bottom thereof.

In Figure 5 I have illustrated a reducing plate 12 which is provided with a central opening 13. This plate is formed with a reduced extension 14 at one end thereof which is provided with depending cleats 15 thereby preventing the same from slipping off of the band 2 when it is situated thereon. A handle 16 is provided on the plate 12 so that the same may be lifted and placed in and out of engagement with the band 2 as may be desired. This reducer plate 12 is also adapted to be used with the band 4 when found desirable.

Having thus described my invention what I claim as new is:—

A device of the class described comprising a U-shaped band, a zig-zag band secured about the U-shaped band to form triangular compartments one opposite each of the legs and body portion of said band, the terminals of said zig-zag band being parallel and extended beyond the legs of the U-shaped band, a semi-circular band, and a zig-zag band, secured about the semi-circular band, the terminals of the semi-circular band and the zig-zag band carried thereby being secured to the free extended ends of the first named zig-zag band.

In testimony whereof I affix my signature.

CARL R. SNODGRASS.
